UNITED STATES PATENT OFFICE.

ALFRED BUSSY, OF PARIS, FRANCE.

SPLINT-FORMING MACHINE.

Application filed June 10, 1926, Serial No. 115,116, and in France June 26, 1925.

The present invention relates to machines for making splints for use in the manufacture of matches as well as for other purposes; and its object, stated briefly, is to provide improved mechanism or devices which will operate with a maximum efficiency in slitting and cutting slices of timber to form splints of rectangular or square section, and in such a way as to reduce the size of the unused portion or core of the timber as much as possible and thereby avoid waste.

According to the invention, the improved machine operates first of all to slit the face of the timber by means of knives or other cutting devices carried by a reciprocating or rocking slide, and then to sever the slit face in slices by means, preferably, of a rotating disk cutter or cutters. The slitting device and the slicing device move or operate in alternation and in directions perpendicular to each other, the latter device being carried by a reciprocating cross-head; and the invention, in its more limited aspects, resides in the particular mounting of the slide and the cross-head, and in the mechanical devices employed for effecting and controlling their movements. These and other improvements involved are fully described and explained hereinafter, and set forth in the appended claims, but it is to be understood that structural modifications and changes may be made in the machine while remaining within the scope of the claims.

The accompanying drawing shows a machine embodying what is now considered the preferred construction of the invention, such machine comprising two slitting devices and two rotary cutters or slicers, the slitting devices having a rectilinear reciprocating movement which, however, can be substituted by a rocking movement if desired.

In said drawing:

Figure 1 is a fragmental side elevation of the machine;

Fig. 2 is a vertical sectional view thereof, the right half on line A—B, and the left half on line C—D, of Fig. 1;

Fig. 3 is a top plan view of Fig. 1.

In the middle of the upper part of the frame 1 are provided dove-tail or rectangular guides 2 for a slide 3 which moves forward and backward. This slide 3—on which one or a plurality of the already-mentioned slitting devices can be secured—is driven by a connecting rod or pitman 5 and a crank (not shown) attached thereto. The

two slitting devices are designated 4, 4 and their characteristic feature is that they can comprise a variable number of superimposed knives or cutters according to the required match sections and to the machine's capacity.

To the frame 1 are secured uprights 6, 6 fitted with guides 7, 7 for a sliding cross-head 8 wherein revolves a shaft 9 carrying two rotary slicing disks 10. Cross-head 8 is provided with two ears 11, between which passes a pivot-stud 12 secured by a nut 13; and on this stud is mounted the upper end of a connecting rod 14, the lower end 15 of which fits slidably in a bearing 16 on frame 1 and carries a bolt 17 equipped with a roller 18.

This roller 18 travels in a groove 19 provided in a cam 20 keyed on a shaft 21 whereon is fixed a sprocket wheel 22, the drive of which is not shown. Shaft 9, carrying the slicing disks 10, is rotated by a worm 24 meshing with a worm wheel 23 thereon, the worm 24 being itself keyed to slide on a longitudinally grooved shaft 25 which also carries a spiral gear 26¹ in mesh with and driven by a similar gear 26² mounted on a horizontal shaft or spindle 27. The latter also carries a sprocket wheel 28 driven by a chain (not shown).

On each side of the frame are positioned wooden timbers 29¹ and 29² connected with a feeding device (not shown) by means of levers and pawls; such arrangement permitting the timbers to be fed accurately so that the slitters will penetrate therewith only to the required extent and in accordance with the adjustment of the rotary slicing disks.

The timbers 29¹ and 29² must have a thickness (in the direction of their grain) equivalent to the length of a match splint or stem, but their width is limited by the height of the machine; that is to say, by the cage carrying the feeding rolls or cylinders, the length of the timbers being a function of the diameter of the shaft.

The operation of the machine is as follows:

On the machine being started, the connecting rod or pitman 5 imparts to slide 3 a reciprocatory motion in the slideway 2 of frame 1. Due to this motion, the slitting device 4 forms cuts in the wood to a depth corresponding to the thickness of a match stem; the spacing of the cutters being equal to the width of a stem. Shaft 21 and cam 20 are constantly rotated when the machine is started and, at the same time, grooved

shaft 25 is driven by wheels 23 and 24 and its rotation is transmitted to the parts on shaft 9 and, hence, to the rotary cutters 10. Cam 20, however, makes two revolutions

- 5 while the crank which actuates pitman 5 makes one, so that, in fact, cam 20 makes two revolutions during a reciprocation of the slitting device 4.

While the slitting device 4 is at work, cam 10 20 occupies the position indicated by its axial line O—B (Fig. 1), the cross-head 8 remaining stationary at the upper part of the frame although shaft 21 is constantly rotating. This is made possible owing to 15 the semi-circular part of groove 19, the result being that the work of the slicing disks 10 is effected during half a revolution only of cam 20. During this second period, roller 18 is compelled to follow the path of the 20 groove from N to O, while pulling downwards the connecting rod 14 and the cross-head 8, the latter sliding between the guides 7. Due to the rotation of the cam, the cutting disks are thus caused to assume the position 25 10^b indicated in dot-and-dash lines in Fig. 1; whereafter, during the travel of roller 18 from O to M and then to B, the cross-head resumes its position at the top of guides 7. At the same time, the rectilinear bearing 16 maintains the connecting rod 14 30 rigid despite the effort of roller 18.

This cycle of movements is repeated during both the forward and the return movement of the slitting device, the latter slitting the wood both on moving forward and on coming back, and the disks 10 slicing off the wood in such a way as to detach the

stems or splints after each slitting stroke. The moving parts are preferably balanced, in order that the power required to operate 40 the cross-head 8 may be as small as possible.

The output of the machine can be increased by increasing the number of slitting devices and of cutting disks.

I claim as my invention:—

1. In a splint-forming machine, a slicing device, a rod connected to operate the same and provided adjacent its lower end with a roller, a continuously-rotating shaft, and a cam fixed to said shaft and having on one 50 face thereof a closed track to receive said roller; such track comprising straight, parallel sides and a semi-circular top and bottom portions.

2. In a splint-forming machine, a vertically-reciprocating cross-head, a rotary slicing device mounted thereon, an operating rod connected to said cross-head, a drive shaft, a cam on said shaft connected to operate said rod, and driving means for rotating 55 said slicing device.

3. In a splint-forming machine, a vertically-reciprocating cross-head, a rotary slicing device mounted thereon, an operating rod connected to said cross-head, a drive 60 shaft, a cam on said shaft connected to operate said rod, a separate shaft for driving the slicing device, and gearing connecting the last-named shaft and said slicing device and including a member which is keyed to 70 that shaft to slide thereon during the movements of the cross-head.

In testimony whereof I affix my signature.

ALFRED BUSSY.
